TUNING MECHANISM

Anthony J. Lombardi, Floral Park, N. Y., assignor
to Sperry Gyroscope Company, Inc., Brooklyn,
N. Y., a corporation of New York

Application February 15, 1943, Serial No. 476,011

5 Claims. (Cl. 178—44)

1

This invention relates to electronic apparatus and is more particularly concerned with tuning mechanism for such apparatus.

In its preferred embodiment the invention will be described as adapted for fine adjustment gang tuning mechanism in electronic apparatus of the hollow resonator type.

For gang tuning a two resonator velocity modulation device, it has become usual to simultaneously vary the input and output electrode spacings in the device. Various fine adjustment mechanisms have been suggested, tested and used for gang tuning in this manner. Many of these have proved unreliable in that they are not capable of reproducible adjustment, some have poor life due to excessive or uneven wear in the parts, and the most reliable adjustments heretofore known are essentially complicated and require many accurately machined parts.

It is therefore the major object of the present invention to provide a novel gang tuning mechanism for electronic apparatus which is inexpensive, simple in construction, reliable and accurate during repeated tuning cycles, and which has a working life comparable to the device in which it is employed.

A further object of the invention is to provide a novel displaceable spherical ball, fine adjustment mechanism for gang tuning in hollow resonator and like electronic devices.

It is a further object of the invention to provide a fine adjustment mechanism for gang tuning in a hollow resonator or other electronic device wherein translational movement of an adjustable tuning control is divided in a novel manner into generally oppositely directed translational forces and movements, angularly related to the direction of movement of said control and acting to simultaneously displace two tuning members in said device. Preferably these opposite movements are equal in amount and at right angles to the driving movement.

A further object of the invention is to provide a novel gang tuning mechanism for obtaining accurately tracking input and output electrode spacing adjustment in a hollow resonator or like electronic device.

Further objects of the invention will presently appear as the description proceeds in connection with the appended claims and the annexed drawing wherein:

Fig. 1 is a side elevation partly broken away and partly in section illustrating a preferred form of my novel gang tuning mechanism;

Fig. 2 is an enlarged fragmentary view com-

2

prising mainly a section along line 2—2 of Fig. 1;

Fig. 3 is a fragmentary elevation in section illustrating an optional construction in the fine adjustment control wherein a tri-ball adjustment is provided;

Fig. 4 is an elevation, partly in section along line 4—4 in Fig. 5, illustrating a further embodiment of the invention;

Fig. 5 is a plan view broken away and in section illustrating details of the tuning mechanism of Fig. 4.

Referring to Fig. 1, which illustrates a velocity modulation device of the two resonator type substantially symmetrical about axis A—A, a pronged base 11 of conventional construction provides a sealed closure for one end of a glass tube 12 enclosing a suitable cathode assembly 13. At its other end, tube 12 is sealed concentrically with a relatively heavy annular metal disc 14, the outer diameter of which is about twice the diameter of the tube 12.

A cylindrical metal barrel 15 provides a common side wall for input and output resonator chambers 16 and 17, respectively. Internally, barrel 15 is formed with a flange 18 for mounting suitably shaped stampings 19 and 21 which comprise the inner end and side walls of the resonator chambers.

An annular flanged rigid collar 22 extends between disc 14 and the annular end wall 23 of chamber 16. Wall 23 is annularly crimped, as illustrated, so as to be flexible in the direction of the axis A—A. A second heavy metal disc 24, preferably identical with disc 14, is similarly rigidly connected to the flexible annular end wall 25 of chamber 17 by a flanged collar 26 similar to collar 22.

Parallel input grid electrodes 27 and 28 are mounted on collar 22 and wall 19, respectively, and parallel output grid electrodes 29 and 31 are mounted on wall 21 and collar 26, respectively. The above-described construction, which is representative of a hollow resonator device for which my invention is primarily adapted, is designed so that displacement of either or both discs 14 and 24 generally in the direction of axis A—A of the device will result in changes in the input and/or output grid spacing because of the flexibility of walls 23 and 25.

In many devices of this nature it is desirable that the spacing of both input and output grids be altered at the same time and by the same amount, and it is to that end that the gang tuning mechanism shown in Fig. 1 is directed.

Intermediate its ends, barrel 15 has rigidly

mounted an external flange 32 to which is secured, as by machine screws (not shown), a heavy metal mounting ring 33. Ring 33 is formed with an external, longitudinally extending peripheral groove 34 for rigidly seating a hollow cylindrical metal guide tube 35 disposed generally parallel to axis A—A. Tube 35 is apertured intermediate its ends to receive a second hollow cylindrical guide tube 36 which is rigidly secured thereto. The axes of tubes 35 and 36 are disposed at right angles, so that a substantially integral T-shaped hollow fitting is provided rigidly secured to ring 33 and having an extension projecting radially outwardly from the device.

While guides 35 and 36 are preferably at right angles, as shown, opposite arms of guide 35 may be made at any desired angle to guide 36 without departing from the spirit of the invention.

Tubes 35 and 36 are internally machined to desired size. Since they are cylindrical, this operation can be accurately and conveniently done. A plurality of spherical balls of the same size are slidably disposed in tube 35, one set 37 being positioned to one side of the axis of tube 36, and the other set 38 being positioned to the other side of the axis of tube 36. While two balls are illustrated in each set, one or any other desired number of balls may be so provided. A spherical ball 39 is slidably disposed within tube 36 so as to partly project into the interior of tube 35 to contact the two adjacent balls 37 and 38.

Ball 39 is shown as of the same diameter as balls 37 and 38, but may be larger or smaller as desired. In any event each ball is selected of such size as to accurately fit snugly but slidably within its supporting guide tube. Preferably, the balls have an outside diameter almost exactly the same as the inner tube diameter so that there is no diametral play. Balls 37—39 are preferably precision-made bearing balls of the type used in high grade ball bearings. Such bearing balls are hardened steel, are accurately spherical, are capable of withstanding extremely heavy radial loads, and are hence admirably suited to the invention.

Outer balls 37 and 38 are contacted by the suitably concaved ends of link pins 41 and 42 which may extend within the opposite ends of tube 35, and pins 41 and 42 in turn have their convex outer ends seated in suitable concave mating surfaces in the ends of coarse adjustment screws 43 and 44 threaded in discs 14 and 24. This in effect comprises a universal link connection between each outer ball 37, 38 and its associated screw. While pins 41 and 42 are shown as independent members, they may, if desired, comprise universally jointed extensions of the screws.

Tube 36 is internally threaded for adjustably mounting a screw 45 having a reduced shank terminating in a hardened planar face 46 at right angles to the tube axis and adapted to contact ball 39. A suitable manual knob 40 is provided on screw 45 for convenience in adjustment.

At points spaced 120° on either side of the above-described fine adjustment mechanism, flange 32 is engaged at opposite sides by the rounded end tips of relatively coarse aligned adjustment screws 47 and 48 threaded in discs 14 and 24. Similarly, the outer peripheries of discs 14 and 24 are interconnected by three equally spaced strong tension springs 49 (only one shown). Springs 49, which are parallel to axis

A—A, tend to draw discs 14 and 24 toward each other, while the coarse and fine adjustment devices above-described positively oppose the pull of the springs.

In practice, the parts are assembled as shown in Fig. 1, screws 43, 44 and 47, 48 providing coarse adjustments for preliminarily setting the device nearly in operating condition. At this point, the rounded tips of each pair of screws 41, 48 is in engagement with opposite sides of ring 33 and the fine adjustment parts are in solid contact, as illustrated. When knob 40 is rotated, screw 45 is translated along the axis of tube 36 to advance driving ball 39 further into tube 35. Such causes the simultaneous and equal outward displacement of balls 37 and 38 in opposite directions, but parallel to axis A—A. This displacement of balls 37, 38 is transmitted through pins 41, 42 and screws 43, 44 to effect relative separation of discs 14 and 24, thereby causing grid 27 to be displaced away from grid 28 by exactly the same amount and at the same time that grid 31 is displaced away from grid 29. This gang tunes the resonators. When screw 45 is rotated in the opposite direction, springs 49 cause the reverse of the above operation and reduce the grid spacings simultaneously and equally. I have found that by this arrangement the input and output grid spacing adjustments track accurately over the tuning cycle life of the resonators.

As discs 14 and 24 are relatively separated or drawn together by action of the fine adjustment mechanism, their relative motion is not exactly parallel, but is rather a pivotal displacement fulcrumed at the rounded tips of screws 47, 48. However, the actual distance moved by the grids during the entire fine adjustment range necessary for tuning the resonators is so small that this departure from actual parallelism is negligible. For example, in a tube of about the actual size shown in Fig. 1, the tuning movement range is only about 0.03 inch.

The above-described fine adjustment is very accurate and reliable, and the two grid spacings track perfectly during the tuning cycle life. Balls 37—39 are in substantially point contact only with each other and their associated guide cylinders at all times so that there is theoretically no friction, and even the small friction which may exist practically can be reduced by providing a suitable lubricant in the T-fitting. I have thus provided a substantially frictionless mechanism for converting motion of translation in a given direction to motion of translation at right angles thereto in opposite directions. Precision-made ball bearings for the purpose are readily and inexpensively available in quantity.

Furthermore, during repeated adjustment, the balls usually become relatively rotated, thereby equalizing the wear on each other and the guides.

Since the forces acting between ball 39 and adjacent balls 37, 38 are radial, the components parallel to the guide axis of guide 35 are small as compared to the force, so that using a suitable thread at 45 almost any desired fine movement can be obtained. All the parts are in solid contact without play, and it is important to note that there is little or no frictional wear on the pins 41, 42 or the threads by screws 43, 44.

My fine adjustment is inexpensive to make as the only accurate machine operations required are reaming of the cylindrical guides, so that considerable savings are effected by the invention.

In the form of the invention shown in Fig. 3,

the reduced inner end of screw rod 45 abuts against ball 39 as in Fig. 1. However, only one ball 37, 38 is here used in each set, pins 41, 42 being made correspondingly longer.

Referring now to Figs. 4 and 5, the fine adjustment mechanism is illustrated as embodying a self-contained subassembly mounted in a cylindrical block 55 which is removably mounted in a suitable socket 56 integral with ring 33, as by set screw 57.

Block 55 is formed with an axial bore 58 threaded at 59 for rotatably mounting adjustable screw 61. Intermediate its ends and disposed to clear socket 56, block 55 is formed with a pair of aligned radial bores 62 and 63 smaller than bore 58. The inner end of screw 61 is a planar face 64 at right angles to the axis of block 55 in contact with a spherical ball 65. Ball 65 in turn is disposed in surface contact with two smaller spherical balls 66 and 67 in bores 62 and 63, respectively. Link pins 41 and 42 contact balls 66 and 67 similarly to the structure shown in Fig. 1.

Bores 58, 62 and 63 are cylindrical guides which may easily be accurately machined to size for slidably receiving the respective balls, as in Fig. 1. Preferably, the outer end of each bore 62 and 63 is slightly deformed, as by a punch prick as indicated at 68, to limit radial outward displacement of balls 66 and 67.

When knob 60 of screw 61 is rotated in one direction, face 64 is displaced along the axis of bore 58 to displace ball 65 and force balls 66 and 67 radially outwardly, simultaneously and over equal distances. The fine adjustment otherwise operates exactly as above-described in Fig. 1. The necessary degree of movement required for resonator tuning is so small that limit stops 68 do not interfere with tuning over the entire normal range. For further limiting the range of adjustment, a stop collar 69 may be provided on screw 61 for limiting axial advance of screw 61 within block 55.

A particular advantage of the construction shown in Fig. 5 is that the sub-assembly on block 55 may be assembled and handled as a unit, and mounted for operation in the device, without danger of any of the balls dropping out. In assembly, ball 65 is dropped into bore 58, with screw 61 retracted. Then balls 66 and 67 are introduced into their respective bores through bore 58, and screw 61 advanced until the balls contact and no ball can escape entirely from its associated bore. Also, the balls 66 and 67 being smaller than ball 65, I find that as a practical matter there is considerably less friction in the

assembly than might be expected from simply reducing their diameters.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:

1. In a fine adjustment mechanism for gang tuning electronic devices and the like, a support having a cylindrical axial bore, a rod mounted in said bore for adjustment axially of said bore, a slideable spherical ball in said bore adapted to be displaced by adjustment of said rod, opposed radial bores in said support and opening into said axial bore, a spherical ball slideable in each of said radial bores, each of said balls being of substantially the same diameter as its respective bore with the balls in said radial bores being substantially smaller than and adapted to contact said first ball, the size differential between the balls in the radial bore and the ball in the axial bore tending to ensure that the latter-named ball is confined to the axial bore during its operative travel, and means for adjusting said rod to effect simultaneous outward displacement of the balls in said radial bores.
2. The gang tuning apparatus defined in claim 1, wherein said balls in said radial bores project outwardly of said support during said adjustment.
3. The gang tuning apparatus defined in claim 1, including stop means for limiting adjustment of said rod.
4. The gang tuning apparatus defined in claim 1, including stop means limiting outward displacement of said balls in the radial bores.
5. In gang tuning apparatus for an electronic device, a substantially T-shaped guide, a spherical ball slidably disposed in each arm and a third spherical ball slidably disposed in the stem of said guide, the arms and stem of said guide each having an internal diameter equal to the respective ball disposed therein with the ball in said stem being larger than each of the other balls and in contact therewith, the size differential between the balls in each arm and the ball in the stem tends to ensure that the latter named ball is confined to the stem during its travel, and means in said stem for displacing the ball therein for effecting simultaneous and opposite outward displacement of the balls in said arms.

ANTHONY J. LOMBARDI.
